WEAVING HEDDLE

Bernhard Robert Koch, Zurich, Switzerland, assignor to
 Grob & Co. A.G., Horgen, Switzerland
 Filed Nov. 23, 1964, Ser. No. 413,171
 Claims priority, application Switzerland, Dec. 19, 1963,

 11 Claims. (Cl. 139—93)

The invention relates to weaving heddles.

There are various known forms of weaving heddles which have end loops joined to the body of the heddle. These known weaving heddles differ one from another owing to the nature of the heddle body, the type of the end loops and the way in which such loops are connected to the heddle body.

That part which extends between the two end loops and which includes one or more eyes to receive warp threads, and if required, further openings is called the body of the weaving heddle. The heddle body can be made from flat steel wire, strip steel or of tinned twin wire, as used for twin wire heddles. The end loops which are to be mounted on the body of the heddle are of a shape determined by the shape and dimensions of the heddle carrying rods. They can either embrace the heddle carrying rods completely, be open at one side (C- or J-shaped) or be hook- or claw-shaped.

Heddles are known with attached one-piece end loops, so-called end loop plates, as well as such with two end loop plates which are individually attached to the end of the heddle body, and such with double end loop part formed by folding.

One-part end loop plates are joined to the heddle body in the known manner by inserting its end into a suited slot-like opening at one end of the plate and soldering or welding it onto same. If the heddle body consists of tinned twin wire, its end may be split and the individual wires bent apart and pressed into suitable openings. In this kind of heddle it is desirable that the weaving heddles, once the end loop plates have been attached, can be transported to the soldering device without changing their position in relation to the heddle body.

To attach a flat steel heddle body to a one-piece end loop plate the end of the body may in the known manner be punched head-shaped and fitted into a suitable cut-out and soldered. A more simple method is, to weld the broad side of a one-piece flat end loop plate to the broad side of the heddle body. This joint however has distinct protruding edges and warp threads may get caught.

It has been suggested that two closely adjacent end loop plates or two individual end loop plates be attached to the heddle body. This requires a welding operation and at the junction the thickening is more distinct, thereby unfavourably influencing the maximum set of heddles.

It has also been proposed to attach one-piece end loop plates to flat steel heddles by different ways of interlacing the end of the heddle body with the end loop plate.

Such connections can be carried out without welding or soldering, however, the one piece end loop where it is folded is about two or three times its thickness and considerably reduces the number of heddles that can be lined up and warp threads can get caught at the various protrusions. To introduce or hook the end of the heddle

2

body into the end loop plate and the subsequent bending operation are an obstacle to quick and economic manufacture.

It is the purpose of the invention to create a weaving heddle with at least one separately manufactured one-piece end loop, which is connected to the heddle body without welding, soldering or bending, by introducing the end of the heddle body into the end loop, which when pressing the latter enters into openings provided therein.

10 Thus, according to the present invention, a weaving heddle including at least one end loop and a heddle body secured thereto, said end loop having superimposed parts between which the heddle body extends is characterised in that the end of the heddle body is held in position 15 in the loop by at least one deviation which is achieved by entering the body into a correspondingly adjusted cut-out in the material of the end loop.

A suited procedure to manufacture this new heddle is that the end of the heddle body is slid into the sleeve 20 shaped end loop and is then distorted by pressing same together.

The invention will now be described further, by way of example only, with reference to the accompanying drawings in which:

25 FIG. 1 shows a lateral view of a twin wire heddle with attached end loops;

FIG. 2 shows the upper end loop of FIG. 1 to a larger scale;

FIG. 3 is a cross-section on the line III—III of FIG. 30 2 to a larger scale;

FIG. 4 is a longitudinal section on the line IV—IV of FIG. 2 to a larger scale;

FIG. 5 shows an alternate form of upper end loop;

FIG. 6 is a cross-section on the line VI—VI of FIG. 5 35 to a larger scale; and

FIG. 7 shows a longitudinal section on the line VII—VII of FIG. 5 to a larger scale;

FIG. 8 is a plan view of a blank employed in forming the end loop; and

40 FIG. 9 is a perspective view of the prefolded blank before being folded side to side and after the heddle end has been inserted.

The weaving heddle as illustrated in FIG. 1 consists of the heddle body 1 with a uniform, laterally open, C-shaped end loop 2 secured to each end thereof. In the embodiment illustrated, the body 1 of the weaving heddle corresponds with that of a twin wire heddle with twin wires arranged juxtaposed in the running direction of the warp. The eye to accommodate the warp thread has been omitted for simplicity's sake. The heddle illustrated shows the end loops 2 at the upper and lower ends of the body, but it is to be appreciated that it would be possible to provide an end loop at one end only.

FIG. 2 shows an upper end loop 2 made of strip steel 55 folded side to side so that the abutment joint 3 does not coincide with one of the two edges. At 4a and 4b longitudinal recesses have been provided at the joint side, into which recesses the twin wire of the heddle body enters.

The cross-section of the end loop 2, as illustrated in 60 FIG. 3, shows how the twin wire of the heddle body 1 enters into the recess 4a. This illustration clearly shows that thanks to the recess 4a the twin wire of the weaving heddle causes no thickening whatsoever of the end loop 2. Such end loops lie flat on each other and can be perfectly

piled contrary to known one-piece end loops, since the thickening that would have been caused by soldering can be avoided.

The longitudinal section as shown in FIG. 4 demonstrates how the end of the heddle body 1, after the introducing thereto and the pressing together of the pre-folded end loop 2 successively enters into the openings 5b, 4b, 5a and 4a provided alternately in the back and front or inner or outer walls of the end loop, the openings being arranged in partly overlapping relationship in said inner and outer walls. Without soldering or welding a connection is created which is not subject to play, and is resistant to pull simply by bending and respectively offsetting successive portions of the end of the heddle body. Also, in the longitudinal direction of the end loop, no thickening is caused by introducing the heddle body end.

A further important advantage of this weaving heddle is that it is sufficient to place the cut-off end of the heddle body into the pre-folded end loop as shown in FIGURE 9 and then completing the fold from side to side as shown in FIGURE 3. Any splitting of the twin wire and bending or spreading of the individual wires is not necessary. Likewise, one has only to cut off the heddle body of flat steel heddles when assembling same. Any fitting form and respective cut-out in the end loop can be saved.

Since the ends of the twin wire forming the heddle body of the twin wire heddle no longer have to be spread this connection can be kept considerably narrower than with the known arrangements. As shown in FIG. 2, the upper part of the connection of a heddle for a riderless weaving frame with C-shaped end loops can by virtue of its small width, also extend to a position adjacent to the cut out for taking up the heddle carrying rod. Thus, it is possible to keep the end loop shorter, by which a saving of raw material, lessening of weight and correspondingly easier movement of the weaving heddle is achieved.

It is no longer necessary to slit the end loop over the full extent of that part of the heddle body which enters the loop and thus the weakening of the body is less.

By virtue of its small width the junction can also be placed near the narrow edge of the end loops formed by a welt. The advantages of this arrangement are described with reference to FIGS. 5 to 7, such figures showing the upper part of a weaving heddle with closed end loop. The end loop 6, into which the end of the heddle body 7 is pressed, also consists of one part and has an abutment joint 8. For example, two in this case round, cut-outs 9a and 9b have been provided, with which the twin wire of the heddle body 7 is engaged. The long cut-out 11 serves to accommodate the heddle carrying rod. In order to reduce weight, oblong slots 12 have been provided. The slots are located either on the front- or joint-side, as can be seen from FIG. 6, or if they are on the front- and rear-side they are staggered relative to each other. Thus it is possible to avoid accumulation of fluff and fly, since the slots are not going right through and their depth is limited.

If the cut-outs in the end loop are staggered and do not even partly coincide, as shown in FIGS. 6 and 7 and if the end loop is made of material well suited for cold working, the twin wire 7 and the end loop material, in areas where no cut-outs are provided, are squeezed when the end loop is closed and pressed flat. At the spot where the heddle body 7 enters into the end loop 6 it is feasible somewhat to chamfer the end loop at 13 to create a conical inlet.

The heddle body 7 lies at one side of the vertical axis running through the cut-out 11 for the upper and lower heddle carrying rod. By reversing alternate heddles having closed end loops on the heddle carrying rods a double rowed heddle set-up can be achieved without the heddle having to be bent twice in the known manner near the upper and lower end loops.

It is in the intention of the invention that the end loop

can be created differently and the positioning, shape and number of the cut-outs be varied. If the material from which the end loops are made can be cold-worked, the cut-outs can be arranged unstaggered. The body of the weaving heddle will enter into the cut-outs on either side or be squeezed between the end loop material.

It is also possible to choose the cut-outs so that only one of the twin wires enters whilst the other enters for example into the opposite cut-out staggered by the thickness of the individual wire.

What I claim is:

1. A weaving heddle including at least one end loop and a heddle body secured thereto, said end loop having superimposed parts forming inner and outer walls between which the heddle body extends, one end of said heddle body being held in position by said parts against frictional displacement, said inner and outer walls being provided with at least one cut-out and said heddle body being provided with a laterally extending offset portion extending into said cut-out to securely hold said heddle body end between said superimposed parts.

2. Weaving heddle as claimed in claim 1 characterised in that the end loop consists of a folded piece of plate with its ends forming a joint, said joint being positioned in one wall of the end loop.

3. Weaving heddle as claimed in claim 2 characterised in that the cut-outs are openings in the plate which forms the end loop.

4. Weaving heddle as claimed in claim 3 characterised in that the openings in the inner and outer walls of the end loop are staggered with relation to each other in the longitudinal direction of the end loop.

5. A weaving heddle comprising spaced end loops and a heddle body extending between said loops and the ends of said heddle body secured to the said end loops, each end loop having two superimposed parts between which the respective end of the heddle body is located and which, furthermore, present openings into which the heddle body extends thus to preclude longitudinal motion of the body relative to the loop.

6. A weaving heddle as claimed in claim 5 wherein the openings in one part are disposed in part overlapping relationship relative to those of the other part.

7. A weaving heddle as claimed in claim 6 wherein the end loop consists of a folded piece of plate having the edges terminating in a joint and a side face area, the joint being positioned in the area of one side face of the end loop.

8. A weaving heddle comprising an end loop formed from a folded plate, a heddle body extending between superimposed parts of the end loop, and detent formations in adjacent opposed walls of the end loop into which the heddle body extends thus to preclude longitudinal movement thereof relative to the end loop, the detent formations of one wall being displaced in the longitudinal direction of the heddle body relative to those of the other wall.

9. A weaving heddle as claimed in claim 8 wherein the plate which forms the end loops is folded side by side so that the edges thereof abut and forms a joint which lies in the area of one wall of the end loop.

10. In the method of making a heddle having a heddle body and an end loop, the steps of locating the end of said heddle body between superimposed parts of an end loop, each such superimposed part having detent formations in alignment with the heddle body and across which the said body extends, and applying pressure to the superimposed parts thus to deform the body and to cause said body to move into the detents.

11. In a heddle structure, comprising an elongated heddle body having alternate offset bent portions, and a heddle loop attached and clamped to the end of the heddle body, said heddle loop having wall portions extending on opposite sides of said heddle body and said wall portions

being provided with offset and staggered openings for receiving said alternate offset bent portions of the heddle body.
